United States Patent Office.

THOMAS H. BROWN, OF CHICAGO, ILLINOIS.

Letters Patent No. 102,762, dated May 10, 1870.

IMPROVEMENT IN BUCK-BOARD SPRINGS.

The Schedule referred to in these Letters Patent and making part of the same.

To all whom it may concern:

Be it known that I, THOMAS H. BROWN, of Chicago, in the county of Cook and State of Illinois, have invented an "Improvement in Carriages;" and I do hereby declare that the following is a full and exact description thereof, which will enable those skilled in the art to make and use the same, reference being had to the accompanying drawings and letters marked thereon making a part of this specification, in which—

Figure 1 is a perspective representation of the body of my carriage.

Figure 2, a longitudinal central sectional elevation of the same.

The nature of the present invention consists in the novel manner in which a box is combined with a buck-board spring, the ends of said box shutting past the ends of the buck-board, so that, when the buck-board springs down, the box may have a free and easy movement, as hereinafter described.

F represents a buck-board spring, composed of slats, which are held in place by cross-bearers G G and D D, being riveted or bolted fast to them.

The end cross-bearers G are properly elevated above the axle-trees J J', and supported by bearers H, which are made of steel and bent upward at their outer ends, so that the middle part of the forward bearer may have a suitable seat on the bearer I, and the middle part of the hind bearer on the hind axle J, and so that the upper ends of these bearers will have flat seats on the under sides of the cross-bearers G, to which they are fastened with bolts or rivets, as most convenient, the middle parts of the bearers being fastened to the bearer I and hind axle in the same manner as the ordinary elliptic carriage-spring.

This arrangement is very different from the ordinary method of fastening a buck-board spring, inasmuch as the latter is bolted fast to the axle-tree, and has a broad bearing of its entire width thereon.

E E represents the sides, and E' E" the ends of a carriage-box, the end E' being broken away to show more clearly the buck-board F.

The sides E are strengthened by ribs B, figs. 1 2, to which are fastened straps C C, provided with threads d d on their lower ends, so that nuts b b turned thereon will draw the cross-bearers D D closely against the lower edges of the aforesaid sides E, and thus hold the middle part of the box and buck-board firmly together.

It will be seen from this description that, if the box is made a little longer than the buck-board, the latter may readily spring down in the center, while the ends of the box pass down by the ends of the buck-board.

In order to prevent the hind axle-tree from twisting under its bearer G, braces K are fastened to the axle-tree near its arms, and also fastened to the under side of the buck-board, as shown in both figures, and, to hold the forward axle-tree in place, a brace, L, is fastened to the middle slat of the buck-board, and pivoted to the coupling-pin on which said axle-tree turns.

By means of this construction and arrangement, a carriage is very much simplified, and the cost of manufacture considerably reduced, while, at the same time, all of the advantages of a buck-board and box are retained.

In the foregoing description I have set forth the entire arrangement of box, but I do not claim the bearers G and braces K L. Neither do I claim the buck-board made of several slats, as they have been used before; but

What I do claim, is—

A spring carriage-box, E E' E", consisting of a buck-board, F, which is attached at its central part to the sides of the box, and which is shorter than the box, so that, when the buck-board springs down, the ends of the box will shut past the ends of the board, as specified.

THOMAS H. BROWN.
